(57) **CLAIM**

We claim the ornamental design for folding handle and operator cover, as shown and described.

DESCRIPTION

FIG. 1 is a front perspective view of a folding handle and operator cover according to an embodiment of the invention with the folding handle in a folded position and, for context, depicted in position on a window sill;

FIG. 2 is a front perspective view of a folding handle and operator cover according to an embodiment of the invention with the folding handle in an unfolded position;

FIG. 3 is a top plan view of a folding handle and operator cover according to an embodiment of the invention;

FIG. 4 is a front elevation view of a folding handle and operator cover according to an embodiment of the invention;

FIG. 5 is a rear elevation view of a folding handle and operator cover according to an embodiment of the invention;

FIG. 6 is a side elevation view of a first side of a folding handle and operator cover according to an embodiment of the invention; and,

FIG. 7 is a side elevation view of the opposing side of a folding handle and operator cover, according to an embodiment of the invention.

The broken lines are for illustrative purposes only and forms no part of the claimed design.
